UNITED STATES PATENT OFFICE.

EBEN N. HIGLEY, OF GREAT FALLS, NEW HAMPSHIRE.

LAST FOR BOOTS AND SHOES.

SPECIFICATION forming part of Letters Patent No. 249,354, dated November 8, 1881.

Application filed August 22, 1881. (No model.)

To all whom it may concern:

Be it known that I, EBEN N. HIGLEY, of Great Falls, in the county of Strafford and State of New Hampshire, have invented a new and useful Improvement in Lasts for Boots and Shoes; and I do hereby declare that the following is a full and exact description thereof, reference being had to the accompanying drawings, making part of this specification—

10 Figure 1 being a side view of a last provided with my improvement; Fig. 2, a bottom view of the same; Fig. 3, a cross-section thereof in a plane indicated by the line xx , Figs. 1 and 2; Fig. 4, a bottom view, representing a modification of the construction.

15 Like letters designate corresponding parts in all of the figures.

In the Letters Patent issued to Levi W. Shorey, February 3, 1880, No. 224,234, a metallic last is described having open grooves under the peg-rows, as distinguished from grooves filled with some sufficiently soft material to receive the projecting points of the driven pegs. The advantages of these open grooves are that 20 the pegs do not interfere with drawing the last from the boot or shoe, and there is no wear or destruction of any part from the drawing of the pegs. The principal objections to a metallic last are its weight and expense. In an application for Letters Patent previously filed by me I have described a last made mostly of wood, but with a thin metallic bottom piece or plate having open pegging-grooves through the metallic plate and reaching into the wood 25 of the last. This construction reduces the weight of the last nearly to that of an ordinary wooden last; but its expense is considerably greater than that of a wooden last. A simple wooden last with open grooves is not practicable, the wood not being sufficiently firm and strong to prevent abrasion and breaking away 30 of the edges of the grooves.

45 My present invention consists in a wooden last having open grooves lined on their sides with iron or other suitable metal for pegging over.

50 In the accompanying drawings, A represents the body of a wooden last. The grooves $a a$ for pegging over are formed in the wood by simply rabbeting the edges of the sole or bottom, then lining the inner side thereof with

a strip or strips, d , of iron or other suitable metal, screwed or otherwise secured to the wood forming the middle part of the sole, as shown. Then a rim or strip, b , (one or more, joined at the ends,) of metal, of sufficient width to form the outer side of the peg-grooves and to lap upward over the sides of the last-body far enough (either throughout its length or at intervals) to fasten it to the sides of the last, is applied. The form of this strip in cross-section, thick at the lower edge and thin or knife-edged at the upper edge, to lap neatly over the wood, as shown in Fig. 3, I prefer, though I do not intend to confine my invention thereto. 65 There might be a thickness of wood outside of this outer metallic lining; but it would be of no particular advantage, would not allow the grooves to be so near the edge of the last as otherwise, and the construction would be 70 more costly than that represented. Besides, it would not be so strong and durable as the one shown; or the lining of the grooves might be made of a single strip of metal bent in U form in cross-section, and covering the bottom 75 as well as both sides of the groove. I prefer, however, the construction represented in the drawings.

One special advantage of this invention, adding greatly to its value, is that by its use I can 80 take worn-out wooden lasts, those rendered unfit for further use as such by the splitting and abrading of the wood where the rows of pegs are repeatedly driven into the last, and make them over into grooved lasts, since the 85 rabbets made in the edges of these lasts cut and clear away all the damaged part, leaving the remainder of the last sound. Thus I am enabled to utilize old lasts and make therefrom my grooved metallic-lined lasts. 90

For such kinds of work as do not have pegs all around the bottom of the boot or shoe, but have nails at the toe and heel, I make only side grooves, $a a$, lined with metal, as shown in Fig. 4, and screw a metallic toe-plate, f , to the toe of the last and a metallic heel-plate, g , to the heel-bottom. At the proper places in the bottom of the last I cut annular grooves to a sufficient depth—say one-half of an inch—and drive therein cylindrical metallic linings $i i$, as shown in Figs. 2 and 3. The wood inside of these lining-tubes at first may be used

without disturbance for tacking into until it is too much split up for holding the tacks well. Then, or when the last is first made, if desired, the wood is cut out inside of the lining-tubes 5 and plugs or disks driven into the tubes, which hold them securely. These disk-plugs are preferably made with the ends of the grain outward, since they do not abrade so fast by the driving of the tacks in consequence. Of course these disks may be replaced as often as necessary.

When old lasts are made over, as above set forth, this method of lining and plugging around the tacking-spots is just suited thereto, 15 the places where the tacks have previously abraded and worn away the wood being selected for lining and cutting away. The heel of the last, where the heel-tack is driven in, may be treated in a similar manner by lining 20 and plugging; but this is not of so much consequence, since the heel-tacks, being driven into the wood there, where the ends of the grain

are outward, do not injure the last so much as do the bottom tacks.

Wooden lasts with grooves to receive strips 25 of some soft material to peg into, and with holding or lining strips of metal outside thereof, have been used, as also grooves in the iron bottoms of lasts to receive some soft material for pegging into. These are clearly distinguished 30 from my invention, since I use open pegging-grooves containing no material.

What I claim as my invention, and desire to secure by Letters Patent, is—

A wooden last for boots and shoes, having 35 open peg-grooves *a a* therein, lined at the sides with metallic linings *b b d d*, substantially as and for the purpose herein specified.

The foregoing specification signed by me.

EBEN N. HIGLEY.
